APPARATUS FOR DISTRIBUTING RAILWAY VEHICLES FROM A MAIN LINE OVER A GROUP OF LINES.

Application filed February 27, 1925. Serial No. 12,027.

My invention relates to improvements in apparatus for distributing railway vehicles from a main line over a group of lines.

My invention is based on the principle of the well known multiple switch and its object is to ensure an efficient shunting service on railway stations. The invention consists essentially in the provision of a plurality of articulated bridge sections supported at their ends on carriages or portable under-frames which are driven through longitudinal shafts and toothed gears from a main motor and a number of auxiliary motors controlled by said main motor.

An embodiment of my invention is illustrated by way of example in the drawings affixed to this specification and forming a part thereof.

In the drawings is:

Fig. 1, a plan of the general arrangement,

Fig. 2, a side-elevation of the supporting carriage and the ends of the bridge girders resting upon it,

Fig. 3, a cross-section on the lines C—D of Fig. 2 through the bridge girder track with the supporting carriage in elevation and

Fig. 4, a cross-section through the supporting underframe on a larger scale.

The general arrangement is as follows:

Between the main track or line E of the arrival group and the distribution lines of the direction group R, Fig. 1, are located a plurality of bridge sections hinged or coupled together by pivots and consisting essentially of two sheet-iron beam girders 10, the ends of which rest upon carriages or under-frames mounted on wheels rolling on tracks

26. The arrangement is such that the bridges in their combined state sweep a fan-shaped area. The distance between the sheet-iron girders of the individual bridges is such that the rails 12 mounted on them form a standard gauge track.

The special arrangement is illustrated by way of example in Fig. 1. In this case there are provided eight bridges or bridge sections B¹, B²—B⁸. The bridges B¹ to B⁷ have each a length of about 12.35 m. The bridge B⁸ has a length of about 20.30 m. The first

bridge B¹ rests with one end on a stationary abutment or block of masonry by means of an axle bearing 16 which permits an angular movement of the bridge within an angle of 6° 72'. The track 12 mounted on the bridge girders connects at the pivot or fulcrum at its end with the main line E on which the trucks 14 to be distributed or sorted are standing coupled together and forming a train. The other end of the first bridge as well as the ends of the other seven bridges are mounted on the portable underframes or carriages indicated by the reference letters U¹ to U⁸, in such a manner that always the two adjacent ends of two bridges rest upon one carriage. One of the ends of a bridge is so firmly combined with the carriage by means of a sliding bearing 18 that only a movement within narrow limits is allowed, to provide for the expansion, of the bridge owing to temperature fluctuations, small displacements and the like. The other end of the bridge is movably mounted on the underframe or carriage by the aid of an axle bearing 20, so that—corresponding with the arrangement of the bridge 1 at the abutment—a lateral movement of all the bridges is rendered possible when the undercarriages travel along their tracks 26.

The junction of the track 12 mounted on the bridge girders at the pivots or joints of the girders is effected by suitable intermediate pieces of rail 22 which are supported on adjacent ends of the bridge girders and are adapted to be moved longitudinally and transversely, see Fig. 4 of the drawings. The extremest end of the bridge B⁸ is again connected with the carriage U⁸ by means of an axle or slide bearing. The rails 12 of the track terminate at the outer end, of the bridge B⁸. During the lateral displacement of the bridges these rail ends pass in front of the ends of the direction or sorting group of rails R which are cut off at right angles.

The bridges in the illustrated example of construction are adapted to be displaced in their pivots or fulcrums by an angle up to 30° 26' in relation to one another. In these extremest positions (limit cases which are

defined by buffers 28.30 the pivots of the bridges B^1 to B^8 are situated on the periphery of a circle of 200 m radius. The pivots of the bridges, the spacing of which amounts to 12.564 m as well as the outer end of the bridge B^8 describe during the travel of the supporting carriages the following paths composed of arcs:

		Distance of travel (M.)
10	Pivot 16 at the abutment	0.00
	Pivot 20 at the underframe U^1	1.5788
	Pivot at the underframe U^2	4.7365
	Pivot at the underframe U^3	9.4728
15	Pivot at the underframe U^4	15.7880
	Pivot at the underframe U^5	23.6820
	Pivot at the underframe U^6	33.1548
	Pivot at the underframe U^7	44.2064
	Extremest end of the bridge B^8	64.3762

20 In view of the fact that the underframes or carriages U^1 to U^8 have to travel different distances when the bridges are moved sideways, it is necessary to move the individual bridges positively. For this purpose longitudinal shafts 32 are disposed between the underframes in line with the axis and are provided with bevel wheels 34, 36 at the ends. At the underframes or supporting carriages the bevel wheels of the longitudinal shafts are geared together by a horizontally disposed bevel wheel 38, Fig. 4. By this arrangement the result is obtained that the driving power of the main motor during the movement of the bridges is transmitted to the driving gears of all the underframes. By correctly proportioning the toothed wheels at the ends of the longitudinal shafts it is furthermore possible to step the driving speed of the various driving devices of the individual underframes U^1 to U^8 in such a manner that

m/sec.

45	Speed of the underframe U^8 amounts to 1.5
45	Speed of the underframe U^7 amounts to 1.03
	Speed of the underframe U^6 amounts to 0.74
	Speed of the underframe U^5 amounts to 0.55
	Speed of the underframe U^4 amounts to 0.37
50	Speed of the underframe U^3 amounts to 0.22
	Speed of the underframe U^2 amounts to 0.11
	Speed of the underframe U^1 amounts to 0.37

55 At the abutment pivot 16 a rotation of the bridge around the axle bearing takes place within the range of the angle of 6° to 72° only, as has already been stated.

60 The electric motor operating the articulated bridge is served from a driver's stand disposed above the under frame. From this stand the distribution of the trucks, the pushing and pulling of the train and the like may also be controlled.

65 A positive connection of the underframes or carriages with their track 26 is attained by a spur wheel 42 driven by the longitudi-

nal shaft meshing with a rack 44 fixed at the side of the inner rail of the underframe runway (see in particular Fig. 4 of the drawings). This provision is necessary in order to eliminate any slip of the wheels of the underframe upon their track. The wheels 42 are fixed on the shafts 32, as far as the bridges B^1 , B^2 , B^3 etc. are concerned and are driven by an intermediate pinion on the bridges B^2 , B^4 , B^6 for getting the movement in the same sense on all bridges.

To avoid excessive torsional stresses in the shaft and to facilitate the starting of the underframes as well as to obtain a uniform motion of the bridges an auxiliary motor 46 is mounted upon each of the underframes U^2 to U^8 . These motors are controlled by the main motor and the pinions upon their rotor shafts engage directly the spur wheels 42 meshing with the racks 44 as is clearly shown in Fig. 4 of the drawings. Automatic solenoid brakes are employed to ensure a sure stopping and correct adjustment of the moving bridges.

25 In the following will be described the manner of operating the arrangement for the splitting up trains on shunting stations.

a. It may first be assumed that a push locomotive is employed. The push locomotive takes up its position at the end of the first train to be split up standing on one of the lines of the arrival group. Meanwhile the articulated turn bridges B^1 , B^8 are adjusted so as to make connection with the line of the direction group R upon which the first group of trucks, which may consist of a single or a plurality of trucks, at the front of the train should be shunted. This group of trucks is already uncoupled from the other parts of the train.

30 From the stand 40 of the driver on the bridge the locomotive which is preferably equipped with electric motors and electric brakes is now set in operation. This locomotive pushes the train across the bridge with an average speed of 1 m per second. As soon as the first group of trucks has passed beyond the range of the bridge so that the edge of the buffer on the truck of the group of trucks to be pushed off the bridge next is just above the race of the bridge, the locomotive is braked, if desired from the driver's stand. The part of the train connected with the push locomotive the couplings of which are preferably kept

35 as short as possible comes to a stop. The wagons to be shunted run a short distance owing to their own, although small momentum which may be increased, if desired, by a slight gradient adjoining the bridge. This short distance suffices to produce a small distance between the separated buffers of adjacent wagons. The articulated bridge is then moved sideways with the part of the train upon it and is adjusted on another line

40 45 50 55 60 65 70 75 80 85 90 95 100 105 110 115 120 125 130

R. During the motion of the bridge the next group of wagons or trucks is uncoupled from the train. The correct adjustment of the bridge track in alignment with the distribution line is rendered possible by automatic solenoid brakes coming into operation at the moment when the main motor and the auxiliary motors are switched out. In this way a locking of the outmost bridge section with the stationary bridge race is rendered unnecessary. When the adjustment of the bridge track has been accomplished, the push locomotive is set in operation again, the train is pushed forward and the next group of wagons is pushed forward on the corresponding line, as already described. This cycle of operations is repeated until all the wagons or trucks have been distributed over the individual lines.

20 The wagons already deposited on the individual direction lines are pushed forward by the following wagons by the length of the group of wagons now to be shunted. Damage to the wagons or trucks or the 25 goods on them is effectively avoided by this method. The direction and grading lines R are utilized in their entire length in this method.

b. Assuming that a capstan is employed 30 for dragging the wagons or trucks of a group on the shunting bridge on a direction line.

Instead by the push locomotive the motion of the train and the splitting up of the 35 groups of the wagons and their distribution over the individual lines may be effected by means of an electric capstan which is located at the forward end of the bridge 8 adjacent to the driver's stand. A change in 40 the principle of the distribution method does not take place hereby. The difference is that the train is dragged when using a capstan.

The new method is by no means inferior 45 to the usual distribution and disposition of the trucks according to the so-called "running-down service." Owing to the simple construction of the elements of the machine reliable and safe operation by the aid of 50 the bridges may be ensured, particularly as stand-by motors may be mounted on the bridge. The distribution and arrangement of the trucks by means of the articulated bridge has the following advantages over 55 the "running down" system:

1. The motion of the train in the improved system takes place substantially on the level ground or on gradients of 1:300. In the running down system the coupled 60 train must be pushed an incline the elevation of which depends upon the distance to be travelled by the trucks and the influences of the temperature and the wind. The lost height of an incline amounts on the average 65 to about 5 to 6 m. In parts where strong

winds occur (12 m per sec.) as for distance at stations along the coast of the sea, the running down inclines must be made so high that the plant on the running down system may prove uneconomical, if not even practically impossible.

2. The trucks to be distributed according to the new method are pushed on to the individual lines. A rolling off of the vehicles which offers difficulties in the running down system particularly in regard to proportioning of the running distance, does not come into consideration any longer. The braking and catching of the vehicles which renders the running down service difficult and which frequently causes damage to vehicles and goods and even derailments is also eliminated. It is, furthermore, doubtful whether the hitherto customary running down system will suffice when the rolling stock is equipped with ball-bearings and the large goods trucks are generally introduced which will probably happen in the near future.

3. By the new distribution method the usual distribution points are also eliminated. The direction lines abut under right angles against the rails of the outer bridge section, in the arrangement illustrated bridge section B⁸. In this manner locking frames are also obviated. As no switches have to be served the service becomes much safer and more independent from frost and snow in winter.

4. Compared with the running down operation the staff can be considerably reduced in the new method. The staff for carrying out the improved method consists of:

A driver who controls the travel of the bridge and its adjustment as well as the moving of the trucks from a suitable driver's stand. If the locomotive is operated electrically the locomotive may be controlled by the driver or a windlass if such be provided,

An assistant for uncoupling the trucks of 110 the train and

One or two further assistants for coupling the trucks in the newly composed train.

5. The first cost for the construction of 115 the articulated turn bridges are on superficial estimate somewhat higher than the cost for an incline but the operating costs of the improved method are considerably lower. The shunting service according to 120 the new method is thus more economical and permits a full utilization of the direction and distribution lines.

It will be readily understood that the details of construction may be altered within 125 the ambit of my claims without departing from the spirit of my invention or sacrificing any of its advantages.

What I claim as my invention is:—

1. Apparatus for distributing railway ve-

hicles from a fixed main line over a group of fixed lines, comprising a plurality of girder sections carrying rails, the extreme sections being adjacent the main line and group of

6 lines respectively, and laterally movable undercarriages for movably interconnecting adjacent sections.

2. Apparatus for distributing railway vehicles from a fixed main line over a group 10 of fixed lines, comprising a group of articulated girder sections carrying rails for connecting said main line with the fixed lines of said group, and means for positively moving said girder sections through a predetermined 15 distance to cause them to lie along definite curves.

3. Apparatus for distributing railway vehicles from a fixed main line over a group 20 of fixed lines, having in combination, a plurality of girder sections carrying rails, said sections being pivotally mounted at one end and substantially rigidly mounted at the other, laterally movable undercarriages, the pivots of all said sections except the first 25 being mounted on said laterally movable undercarriages, and each undercarriage rigidly supporting the end of the preceding section.

4. Apparatus for distributing railway vehicles from a main line to a group of lines, 30 comprising in combination, a group of articulated girder sections carrying rails for connecting said main line with the lines of said group, means for positively moving said 35 girder sections through predetermined distances to lie along definite curves, and a block of masonry for supporting that end of the girder section adjoining the main line.

5. Apparatus for distributing railway vehicles from a main line to a group of lines, 40 comprising in combination, a group of articulated girder sections carrying rails for connecting said main line with the lines of said group, and means for positively moving said 45 girder sections through predetermined distances to lie along definite curves not exceeding a radius of curvature of 200 meters.

6. Apparatus for distributing railway vehicles from a main line to a group of lines, 50 comprising in combination, a group of articulated girder sections carrying rails for connecting said main line with the lines of said group, means for positively moving said 55 girder sections through predetermined distances to lie along definite curves, and relatively short pieces of rail adapted to be moved longitudinally and transversely on adjacent ends of girder sections for connecting the rails of such sections.

60 7. Apparatus for distributing railway vehicles from a main line to a group of lines, comprising in combination, a plurality of articulated girder sections carrying rails, undercarriages for moving said sections, a main 65 motor on one of said undercarriages for ac-

tuating movement thereof, and auxiliary motors controlled by said main motor on the other of said undercarriages.

8. Apparatus for distributing railway vehicles from a main line to a group of lines, 70 comprising in combination, a plurality of articulated girder sections carrying rails, undercarriages for moving said sections, driving mechanism for each undercarriage proportioned to drive said undercarriages at 75 predetermined relative speeds, and common motor means for actuating the driving mechanisms of a plurality of said undercarriages.

9. Apparatus for distributing railway vehicles from a main line to a group of lines, 80 comprising in combination, a plurality of articulated girder sections carrying rails, undercarriages for moving said sections, driving mechanism for each undercarriage proportioned to drive said undercarriage at 85 predetermined relative speeds, common motor means for actuating the driving mechanisms of a plurality of said undercarriages, and auxiliary motor means on such carriages for relieving the driving mechanisms thereof 90 from driving stresses.

10. In apparatus for distributing railway vehicles from a main line over a group of lines by means of a ray-like spreading multiple switch said multiple switch consisting 95 of a plurality of individual bridge sections pivoted together and adapted to be relatively displaced in a horizontal plane, the end of said first section adjoining the main line being adapted to rest upon a stationary masonry block, a bearing upon said block for said section and under-carriage upon which the end of said first section and the ends of the remaining sections of said bridge are adapted 100 to rest, two adjacent ends of said sections being adapted to rest upon one under-carriage, one end of said sections being stationary and the other end capable of moving upon said under-carriage, and short intermediate rail pieces at the joints adapted 105 to be longitudinally and transversely moved on adjacent bridge girder ends, an electric main motor mounted on the extremest under-carriage and shafts and transmission gears controlled by said motor and adapted to 110 drive said under-carriages and to move them positively.

11. In apparatus for distributing railway vehicles from a main line over a group of lines by means of a ray-like spreading multiple switch said multiple switch consisting of 115 a plurality of individual bridge sections pivoted together and adapted to be relatively displaced in a horizontal plane, the end of said first section adjoining the main line being adapted to rest upon a stationary masonry block, a bearing upon said block for said section and under-carriage upon which the end of said first section and the ends of the remaining sections of said bridge are adapt- 120

125

130

135

- ed to rest, two adjacent ends of said sections being adapted to rest upon one under-carriage, one end of said sections being stationary and the other end capable of moving 5 upon said under-carriage, and short intermediate rail pieces at the joints adapted to be longitudinally and transversely moved on adjacent bridge girder ends, an electric main motor mounted on the extremest under- 10 carriage, longitudinal shafts between said under-carriages disposed along the axis of said bridge, bevel wheels upon the ends of said shafts, said wheels being proportioned according to the required travelling speeds, 15 horizontal bevel wheels meshing with said vertical bevel wheels and means for connecting said shafts with said motor adapted to drive said under-carriages and to move them positively. 20 12. In apparatus for distributing railway vehicles from a main line over a group of lines by means of a ray-like spreading multiple switch said multiple switch consisting of a plurality of individual bridges sections 25 pivoted together and adapted to be relatively displaced in a horizontal plane, the end of said first section adjoining the main line being adapted to rest upon a stationary masonry block, a bearing upon said block 30 for said section and under-carriage upon which the end of said first section and the ends of the remaining sections of said bridge are adapted to rest, two adjacent ends of said sections being adapted to rest upon one under-carriage, one end of said sections being 35 stationary and the other end capable of moving upon said under-carriage, and short intermediate rail pieces at the joints adapted to be longitudinally and transversely moved 40 on adjacent bridge girder ends, an electric main motor mounted on the extremest under-carriage, longitudinal shafts between, said under-carriages disposed along the axis of said bridge, bevel wheels upon the ends of said shafts, said wheels being proportioned 45 according to the required travelling speeds, horizontal bevel wheels meshing with said vertical bevel wheels and means for connecting said shafts with said motor adapted to drive said under-carriages and to move them positively, the positive drive consisting of spur wheels on the driving shafts and racks parallel with the inner rails of said under-carriages and engaged by said spur wheels. 50 13. In apparatus for distributing railway vehicles from a main line over a group of lines by means of a ray-like spreading multiple switch said multiple switch consisting of a plurality of individual bridges sections 55 pivoted together and adapted to be relatively displaced in a horizontal plane, the end of said first section adjoining the main line being adapted to rest upon a stationary masonry block, a bearing upon said block for said section and under-carriage upon which 60 the end of said first section and the ends of the remaining sections of said bridge are adapted to rest, two adjacent ends of said sections being adapted to rest upon one under-carriage, one end of said sections being 65 stationary and the other end capable of moving upon said under-carriage, and short intermediate rail pieces at the joints adapted to be longitudinally and transversely moved 70 on adjacent bridge girder ends, an electric main motor mounted on the extremest under-carriage, longitudinal shafts between, said under-carriages disposed along the axis of said bridge, bevel wheels upon the ends of said shafts, said wheels being proportioned 75 according to the required travelling speeds, horizontal bevel wheels meshing with said vertical bevel wheels and means for connecting said shafts with said motor adapted to drive said under-carriages and to move them positively, the positive drive consisting of spur wheels on the driving shafts and racks parallel with the inner rails of said under-carriages and engaged by said spur wheels, and auxiliary electric motors 80 on all the other bridge sections controlled by said main motor and adapted to engage directly with said spur gearing for the purpose of relieving said shaft. 85 14. In apparatus for distributing railway vehicles from a main line over a group of lines by means of a ray-like spreading multiple switch said multiple switch consisting of a plurality of individual bridges sections 90 pivoted together and adapted to be relatively displaced in a horizontal plane, the end of said first section adjoining the main line being adapted to rest upon a stationary masonry block, a bearing upon said block for said section and under-carriage upon which 95 the end of said first section and the ends of the remaining sections of said bridge are adapted to rest, two adjacent ends of said sections being adapted to rest upon one under-carriage, one end of said sections being 100 stationary and the other end capable of moving upon said under-carriage, and short intermediate rail pieces at the joints adapted to be longitudinally and transversely moved 105 on adjacent bridge girder ends, an electric main motor mounted on the extremest under-carriage, longitudinal shafts between, said under-carriages disposed along the axis of said bridge, bevel wheels upon the ends of said shafts, said wheels being proportioned 110 according to the required travelling speeds, horizontal bevel wheels meshing with said vertical bevel wheels and means for connecting said shafts with said vertical motor adapted to drive said under-carriages and to move them positively, the positive drive consisting of spur wheels on the driving shafts and racks parallel with the inner rails of said under-carriages and engaged by said spur wheels, and auxiliary 115 electric motors on all the other bridge sections controlled by said main motor and adapted to engage directly with said spur gearing for the purpose of relieving said shaft. 120 15. In apparatus for distributing railway vehicles from a main line over a group of lines by means of a ray-like spreading multiple switch said multiple switch consisting of a plurality of individual bridges sections 125 pivoted together and adapted to be relatively displaced in a horizontal plane, the end of said first section adjoining the main line being adapted to rest upon a stationary masonry block, a bearing upon said block for said section and under-carriage upon which 130 the end of said first section and the ends of the remaining sections of said bridge are adapted to rest, two adjacent ends of said sections being adapted to rest upon one under-carriage, one end of said sections being stationary and the other end capable of moving upon said under-carriage, and short intermediate rail pieces at the joints adapted to be longitudinally and transversely moved on adjacent bridge girder ends, an electric main motor mounted on the extremest under-carriage, longitudinal shafts between, said under-carriages disposed along the axis of said bridge, bevel wheels upon the ends of said shafts, said wheels being proportioned according to the required travelling speeds, horizontal bevel wheels meshing with said vertical bevel wheels and means for connecting said shafts with said vertical motor adapted to drive said under-carriages and to move them positively, the positive drive consisting of spur wheels on the driving shafts and racks parallel with the inner rails of said under-carriages and engaged by said spur wheels, and auxiliary electric motors on all the other bridge sections controlled by said main motor and adapted to engage directly with said spur gearing for the purpose of relieving said shaft.

electric motors on all the other bridge sections controlled by said main motor and adapted to engage directly with said spur gearing for the purpose of relieving said shaft, and a driver's stand at the extremest end of said bridge from which the attendance and control of the entire plant viz. the

lateral displacement of the bridge and the pushing or drawing of the trucks on the bridge and the distribution lines can be effected with the assistance of a small staff. 10

In testimony whereof I have affixed my signature.

JOHANNES FEUERLEIN.

Certificate of Correction.

It is hereby certified that in Letters Patent No. 1,585,337, granted May 18, 1926, upon the application of Johannes Feuerlein, of Zehlendorf, near Berlin, Germany, for an improvement in "Apparatus for Distributing Railway Vehicles from a Main Line Over a Group of Lines," an error appears in the printed specification requiring correction as follows: Page 4, line 85, claim 9, for the word "undercarriage" read *undercarriages*; and that the said Letters Patent should be read with this correction therein that the same may conform to the record of the case in the Patent Office.

Signed and sealed this 13th day of July, A. D. 1926.

[SEAL.]

M. J. MOORE,
Acting Commissioner of Patents.
